United States Patent Office.

STEPHEN SPOOR, OF PHELPS, NEW YORK.

Design No. 3,488, dated May 11, 1869.

DESIGN FOR A LAMP-PEDESTAL.

The Schedule referred to in these Letters Patent and making part of the same.

To all whom it may concern:

Be it known that I, STEPHEN SPOOR, of Phelps, in the county of Ontario, and State of New York, have invented a new Design for a Lamp-Pedestal; and I do hereby declare that the following is a full and exact description thereof, reference being had to the accompanying drawings, making part of this specification—

Figure 1 being an elevation of the lamp-pedestal;
Figure 2, a plan of the same, taken from the plane
 z , fig. 1.

Like letters designate corresponding parts in both figures.

Upon the base A are plinths B C D, each succeed-

ing plinth above being of somewhat less breadth than the one next below, so as to leave a narrow ledge bordering it upon the said next lower plinth.

The shaft E extends from the middle of the upper plinth upward to the body of the lamp.

What I claim as my invention, and desire to secure by Letters Patent, is—

The form and configuration, substantially as herein described and shown, composing a design for a lamp-pedestal.

STEPHEN SPOOR.
